UNITED STATES PATENT OFFICE

2,122,680

REFRIGERATION MEANS

William F. Dart, Mason, Mich.

Original application March 8, 1934, Serial No. 714,717. Divided and this application April 17, 1935, Serial No. 16,856

3 Claims. (Cl. 62—89)

This application is a division of my co-pending application, Serial No. 714,717, filed March 8th, 1934, which has now matured into Patent No. 2,051,132, issued Aug. 18, 1936.

5 This invention relates to a closure for refrigerators and like containers of the above stated character which will permit the refrigerator to be fully opened when desiring to remove or replace articles from the food compartment, and 10 which will permit exposure of the ice cube chamber when desiring to obtain ice, so that atmospheric temperatures will not readily enter the food compartment and unnecessarily raise the temperature therein, consequently permitting the 15 refrigerator to be more economically operated and the temperature within the refrigerator more evenly maintained, assuring a better preserving of food products over a longer period of time.

The primary object of the invention is the 20 provision of inner and outer doors mounted for simultaneous opening and closing of the refrigerator and capable of being operated, so that the inner door may remain closed for the closing of the food compartment during the opening of 25 the outer door, while at the same time giving admittance to the ice cube chamber.

Figure 1 is a fragmentary perspective view 30 illustrating a refrigerator equipped with a door construction constructed in accordance with my invention.

Figure 2 is a fragmentary horizontal sectional view showing the inner and outer doors latched together and occupying door-closing position.

Figure 3 is a similar view showing the inner 35 and outer doors moved simultaneously to an open position for exposing the interior of the refrigerator.

Figure 4 is a similar view showing the outer door occupying an open position while the inner door occupies a closed position and exposing the rack of the inner door so that articles may be readily placed in and removed therefrom.

Figure 5 is a fragmentary sectional view showing 45 the means of latching the inner and outer doors together and also a spring catch for aiding in maintaining the inner door in a closed position when the outer door is released therefrom and swung to an open position.

Figure 6 is a detail sectional view taken on the 50 line 6—6 of Figure 5.

Figure 7 is a disrupted view showing one of the hinges.

Figure 8 is a fragmentary view showing the latch for securing the outer door in closed position and the finger piece of the latch employed

for securing the inner and outer doors together.

Figure 9 is a fragmentary view showing one of the hinges.

Referring in detail to the drawings, the numeral 5 indicates a conventional type of refrigerator wherein the cooling unit is shown at 2 and is of the type to freeze ice cubes or blocks, the remaining interior of the refrigerator being employed for the storage of food products and the like. Heretofore when obtaining ice from the freezing or 10 cooling unit it was necessary to expose the entire interior of the refrigerator to atmospheric temperatures, causing an unnecessary raising of the temperature of the refrigerator and increasing the cost of operation and maintenance, and to 15 overcome these disadvantages my invention is employed and is in the form of a closure hingedly mounted to the refrigerator and includes inner and outer doors 2' and 3 both supported to the refrigerator 1 by hinges 4, capable of permitting 20 the doors to swing simultaneously or one independent of the other. The inner door 2' is shaped so that when in closed position, will expose a freezing or cooling unit 2 while the food compartment is closed to the atmosphere. The outer 25 door 3 is of the chambered or flanged construction forming upon the interior face thereof a chamber or space 5 to receive a rack 6 supported by the outer face of the inner door when said doors engage with each other or when latched together 30 which will be hereinafter more fully described. The rack 6 may be employed for various articles not needing very low temperatures for their preservation and when the outer door 3 is opened independently of the inner door, the rack 6 becomes 35 fully exposed so that articles may be readily placed in and removed therefrom.

A spring catch 7 is carried by the refrigerator to engage with the inner door for aiding in retaining the latter in a closed position when the 40 outer door is swung open. The catch 7 is of a conventional type, that is employing a spring pressed ball engageable with a notch or socket formed in the inner door.

The outer door is equipped with a conventional 45 type of latch 8 to engage with a keeper 9 on the refrigerator 1 for retaining the outer door in a closed position and is operable by a handle 10 when desiring to free the outer door for movement into an open position.

A keeper 11 is carried by the outer face of the inner door and enters the chamber 5 when the inner and outer doors are in abutting engagement and is engaged by a latch 12 carried by the outer door where said doors will be fastened together. 55

The latch consists of a member 13 journaled in a bracket 14 carried by the outer door and has formed upon its inner end an angularly disposed projection or arm 15 to engage with the keeper 11. Slidably mounted in the outer wall of the outer door is a tubular finger piece 16 which slidably receives the member 13 and the latter is provided with spiral grooves 17 engaged by a lug 18 formed on the finger piece 16 whereby end- wise movement of the finger piece will impart rotation to the member 13. A coil spring 19 is interposed between the bracket 14 and the inner end of the finger piece 16 for normally urging the latter in one direction or in a direction to cause rotation of the member 13 for positioning the arm 15 in engagement with the keeper 11. A manual movement of the finger piece in an opposite direction causes reverse rotation of the member 13 to disengage the arm 15 from the keeper 11. It is preferable that the finger piece 16 be located in close proximity to the handle 10 of the latch 8 so that a person operating the handle 10 to free the outer door may also operate the latch 12 to free said outer door from the inner door, permitting the latter to remain in closed position. When desiring to open both doors simultaneously the operator simply releases the outer door by actuating the handle 10 to release the latch 8 from the keeper 9 and both doors may then be swung simultaneously to an open position.

Having thus described my invention, what I claim as new and desire to secure by Letters Patent, is:—

1. The combination with a refrigerator comprising a heat insulating cabinet open at one side, a heat insulating door for closing the open

side of said cabinet, a cooling unit mounted in the storage compartment enclosed by said cabinet to cool said compartment and a freezing chamber associated therewith adjacent said door, of a removable shield disposed in the open side of said cabinet adjacent said door to close the open area around said freezing chamber whereby the cold air is retained in the storage compartment when the door is opened to enter the freezing chamber.

2. In a refrigerator the combination of a heat insulating cabinet having an open portion, a heat insulating door closing said open portion, a cooling unit comprising means for dividing the space within said cabinet into a freezing chamber surrounded by a cold storage compartment, and a pivotally mounted shield disposed within said open portion to close the open area around said freezing chamber, whereby cold air is retained in the cold storage compartment when the door is open to enter the freezing chamber.

3. Refrigerating apparatus comprising in combination, a cabinet having a food compartment and a door opening, a door for closing said opening, a refrigerant evaporating element within said cabinet for cooling said compartment, a pivotally mounted shield in the rear of said door and spaced therefrom to provide a space therebetween, said shield being provided with a cutaway portion for gaining access to said evaporating element, and being arranged to be swung outwardly for gaining access to said food compartment, and a plurality of shelves mounted on the outside of said shield and at the side of and below said cutaway portion.
